UNITED STATES PATENT OFFICE.

EDGAR ROUSE SUTCLIFFE, OF LEIGH, ENGLAND.

KILN.

1,061,952.

Specification of Letters Patent.

Patented May 13, 1913.

Application filed February 2, 1912. Serial No. 675,061.

To all whom it may concern:

Be it known that I, EDGAR ROUSE SUTCLIFFE, a subject of the King of Great Britain, residing at Leigh, in the county of Lancashire, England, have invented certain new and useful Improvements in Kilns, of which the following is a specification.

This invention relates to improvements in the construction of kilns for burning ore 10 briquets, ordinary clay bricks, or other earthenware, goods, and the like.

The object of the invention is to improve the firing arrangement of such kilns, and especially to provide that the heating gases 15 shall be of a neutral character as regards their reducing, or oxidizing condition.

The accompanying drawings illustrate a form of the invention as applied to a continuous kiln for burning bricks.

20 Figure 1 is a plan of the kiln. Fig. 2 is an elevation, partly in section of Fig. 1; the left hand portion being on the line C—D, and the center portion on the line E—F of Fig. 1. Fig. 3 is a section of the kiln on the line A—B of Fig. 1 to an enlarged scale, and Fig. 4 shows a modified form of the air 25 supply flue.

Referring to the drawings it will be seen that Fig. 1 shows on the left hand side a 30 plan on the ground line, in the middle a plan of the top of the kiln, and on the right hand side a sectional plan through the hot air flues.

This invention consists, firstly, in the construction of a transverse flue *g* beneath the floor of the kiln at one end of each chamber 35 immediately beneath the fire grate *c* thereof, and in connecting the ends of such flues with an air tube *l* and steam nozzle *m* by 40 means of which a regulated amount of either steam and fresh air mixed, or steam and hot air, can be forced under pressure up through the fire grate *c* and fuel; and secondly, in the provision of a series of air 45 inlets *n* along the whole length of the furnace, immediately above the grating *c*, so that air for combustion may be equally distributed throughout the furnace and a completely neutral gas is obtained for the burning 50 of the goods *i. e.* a gas which neither has a reducing, nor an oxidizing effect on the goods; this is an essential of great importance in the burning of ore briquets.

55 In the drawing is shown a double row, multiple chamber kiln with twelve chambers 12, each chamber having

a fire grate such as *a*, *b*, *c*, transversely across it and adjoining one of its boundary walls such as *d*, *e*, *f*, in which are openings such as *n* in Fig. 3 for the admission of air over 60 the fire.

The transverse flues in the floor of the chamber are shown at *g* beneath the grate *c*, being connected at their inner ends to an upright extension *g*¹ in the central dividing 65 wall *i* of the kiln; the air tube may also be applied to a horizontal continuation of the base flue *g* leading to the outside of the kiln at the ground level, and in a kiln having a single line of chambers this latter form 70 would always be employed. This fire grate flue *g*¹ is provided with frames *k* *k*¹ where it opens through the floor of the flue *j* and the roof of the kiln respectively; a hole is left therein through which an iron air tube 75 *l* may be inserted so as to reach into the flue *g*¹; into the bell mouth of this air tube *l* a steam pipe *m* is introduced and a jet of steam caused to enter; this has the effect of forcing a considerable quantity of air and 80 steam through the flue *g* and up through the fire grate *c* upon which the fuel is placed. The flue *g* though continued so as to reach the outside of the kiln is there closed by a 85 damper *h*; in the event of the gas feeding apparatus just described not being in use this damper *h* would be opened and fresh air would reach the fire grate in this way though not of course under any pressure. When the injector apparatus is withdrawn 90 from the frames *k* *k*¹ the holes therein are closed with caps or covers fitting thereover.

The special advantage of the mixture of air and steam under pressure being supplied to the grate, is that gas is produced above 95 the fuel and burned in combination with the air for combustion entering through the openings such as *n* in the division wall of the chamber which also forms one side of the furnace, the other side being formed by the 100 dwarf wall *p*.

The steam nozzle *m* can either be permanently provided for each air tube *l* or a flexible pipe and nozzle can be used to bring the steam to each air tube as required; the tubes may themselves be removable if desired, covers *k* *k*¹ being used to close the insertion holes.

In a modification the steam nozzle *m* and air tube *l* may open within a hot air flue *j* 110 formed longitudinally along the double chamber kiln and the air injected into the

base flue g will thus be at a high temperature.

In either type of kiln hot air from the previous chamber will enter through openings n in the dividing wall above the grate and will thus supply heat for combustion of the fuel thereon, in addition to the steam, or steam and air mixture, coming through the grate from the base flue.

10 The grate will be fed with small coal in the ordinary way by firing holes in the top of the kiln, and the fire will be separated from the body of the chamber by a dwarf wall p so that it does not come into contact 15 with the goods being burned.

Other details of the kiln are such as are in common use, for instance the longitudinal hot air flue j with connecting flues such as q r to the several chambers by which hot 20 air may be brought in or taken away therefrom for preliminary drying, and the damper flues s , t , by which when the damper u is open, the products of combustion pass out of a chamber and away to the chimney 25 through the smoke flues v having first traversed a number of the chambers. Also the operation of such a kiln is so well known as not to need further description, but by the use of this invention all the benefits of 30 such a kiln worked with what is known as "producer" gas from a separate gas producer are achieved with much greater efficiency both in time and material.

It should be understood that in certain 35 cases the down flues g^1 and q may be combined, utilizing the same flue alternately for the supply of hot air for drying purposes and for the supply of air for combustion. Further instead of taking the air for combustion from the outside of the kiln the 40 opening of the air tube may be in the hot air flue as shown dotted (Fig. 3), thus hot air for combustion may be supplied which is of great advantage in obtaining efficiency.

45 Fig. 4 shows a modification in which the air supply and hot air flues are combined. The down flue g^1 is divided into four compartments each compartment in separate connection with a horizontal length entering the transverse flue g at a different point beneath the floor of the chamber. By intro-

ducing the air at several points in the fire grate flue g and regulating the flow of air in the several divisions a much better control of the fire transversely is obtained; in 55 such a case a separate air tube would be required for each division of the flue g^1 .

What I claim as my invention and desire to secure by Letters Patent is:—

1. The combination in a kiln chamber, of 60 a transverse furnace grating at the floor level adjoining a chamber partition wall, a transverse flue beneath same, an extension flue from the transverse flue to the outer air passing across a hot air flue, an air tube to 65 same arranged to open either in the hot air flue or in the outer air, a steam injector pipe coöperating with the air tube, a chamber partition wall forming one side of the furnace and having distributed openings 70 therein for the purpose of introducing a regularly distributed air supply to the furnace above the grating, and a dwarf wall forming the opposite side of the furnace, all substantially as and for the purpose set 75 forth.

2. The combination in a kiln chamber, of 80 a transverse furnace grating at the floor level adjoining a chamber partition wall, a transverse flue beneath same, a subdivided extension flue from the transverse flue to the outer air passing across a hot air flue, and having its sub-divisions opening into the transverse underground flue at different 85 points in its length, an air tube to each subdivision of the extension flue arranged to open either in the hot air flue or in the outer air, a steam injector pipe coöperating with each air tube a chamber partition wall forming one side of the furnace and having distributed openings therein for the purpose of introducing a regularly distributed air supply 90 to the furnace above the grating, and a dwarf wall forming the opposite side of the furnace, all substantially as and for the 95 purpose set forth.

In testimony whereof I affix my signature, in presence of two witnesses.

EDGAR ROUSE SUTCLIFFE.
